DESOLDERING IMPLEMENT OR THE LIKE

William S. Fortune, 14250 Dearborn St.,
Panorama City, Calif. 91402

Filed Apr. 2, 1968, Ser. No. 11,269

Term of patent 14 years

Int. Cl. D8—02

U.S. Cl. D26—1

FIGURE 1 is a plan view of an example of a desoldering implement or the like embodying the claimed design having an axially movable plunger element shown inserted relatively within the main body portions thereof; FIGURE 2 is a bottom view thereof;

FIGURE 3 is a left side elevational view thereof showing said plunger element relatively extended from within said main body portions; the shaft of the plunger element is shown broken to indicate additional length thereof, its total length being approximately equal to that of said main body portions; the right side elevational features of the claimed design being substantially a mirror image of those shown in this figure; and

FIGURE 4 is a side elevational view of a portion of a modified form thereof; this form being distinct by virtue only of the illustrated difference in the knob member disposed at the right-hand end, as viewed in the figures, of the plunger element.

The undisclosed face of the knob member is plane and unornamented.

I claim:

The ornamental design for a desoldering implement or the like, substantially as shown and described.
